ELECTRIC SWITCH

Filed Nov. 25, 1924

Fig. 1.

Fig. 2.

Fig. 3.

A hand-drawn diagram of a curved, segmented structure, likely a model of a ribcage or similar. The structure is composed of several parallel lines forming a series of arches. Numbered labels are placed along these lines: '3' is at the bottom left, '3' is at the bottom right, '3' is at the top left, '6' is at the top center, '3' is at the top right, and '1' is at the far right end. The label 'Fig. 5.' is written above the structure.

HENRY A. HOESCHEN, OF OMAHA, NEBRASKA.

ELECTRIC SWITCH.

Application filed November 25, 1924. Serial No. 752,126.

The invention relates to electric switches and to that class of electric switches wherein circuits are closed and opened by a movable body of conductive fluid, operating in a semi-spherical curvilinear double wall tube formed from insulating material, preferably glass or enamel lined material, which is non-conductive; a plurality of chambers extending downwardly from the lower extremity 10 of the tube, said chambers carrying a portion of the conductive fluid, in which fluid the lower ends of terminal wires are submerged. The terminal wires may be carried in any desired direction through the 15 walls of the tube, either inwardly into the hollow chamber thereof, outwardly or downwardly, or upwardly through the upper extremity of the tube and applied to binding posts from whence electric current may be 20 conveyed.

A further object is to use mercury as a conductive fluid in predetermined quantities in the tube. Also to provide a reservoir situated in the interior of the tube, adjacent 25 to and slightly above the movable body of conductive fluid, and in which reservoir a reserve supply of fluid may be stored and added to the body of fluid as desired by tilting of the tube, or a portion of the conductive fluid may be transferred to the 30 reservoir as desired, thereby allowing the amount of fluid in the conductive body to be varied as desired. The reservoir is preferably hermetically sealed, and which sealing 35 will not interfere with the apportioning of the fluid.

A further object is to fill the unoccupied space of the tube with an inert gas, the gas having no chemical affinity for the mercury, 40 or for the material in the tube; the inert gas being approximately an atmospheric pressure.

A further object is to provide an electric switch particularly adapted for use in connection with intermittent sign lighting, and comprising a tube pivotally and tiltably supported on a standard and provided with a conductive fluid raceway in which is disposed a semi-circular conductor wire leading 45 to a source of power and a plurality of contact wires extending downwardly into mercury receiving pockets, and connected to binding posts, and which are placed in circuit with the semicircular shaped conductor 50 wire through the medium of the mercury 55

during the oscillatory movement of the tube. Also to provide the tube with a downwardly extending yoke in which is rotatably mounted an eccentric and which eccentric, during the rotation thereof, oscillates the tube for 60 causing the mercury therein to pass around the raceway therein for intermittently closing and opening the circuits.

With the above and other objects in view the invention resides in the combination 65 and arrangement of parts as hereinafter set forth, shown in the drawing, described and claimed, it being understood that changes in the precise embodiment of the invention may be made within the scope of what is claimed 70 without departing from the spirit of the invention.

In the drawings:

Figure 1 is a vertical transverse sectional view through the switch showing the same 75 tilted.

Figure 2 is a view in elevation of the device.

Figure 3 is a horizontal sectional view 80 through the device taken on line 3-3 of Figure 1.

Figure 4 is a detail perspective view of the lower portion of one side of the tiltable member showing the mercury body contacting 85 with the wire terminals.

Figure 5 is a view similar to Figure 4, showing a further movement of the mercury body.

Figure 6 is a view similar to Figure 4 showing a still further movement of the 90 mercury body.

Figure 7 is a view similar to Figure 4 showing a further position of the mercury body.

Referring to the drawing, the numeral 95 1 designates a semispherical double wall 2 in inverted position, and 2 the inner wall thereof. Extending downwardly from the lower side of the tube at spaced intervals is a plurality of chambered members 3, in 100 which mercury collects. Connected to the binding posts 4 carried by the base 5 of the device are upwardly extending wires 6, which wires preferably extend upwardly into the semispherical member 1, and through 105 the wall 2 thereof as at 7 and thence downwardly and have their ends disposed in the chambered members 3 in the mercury therein. Wires 6 have sufficient slack where they 110 will not interfere with the oscillatory tilt-

ing movement of the semispherical member 1, which is supported on the conically shaped end 8 of the supporting post 9 carried by the base 5. Disposed within the 5 lower end of the conductor fluid chamber 10 is a semicircular conductor wire 11, which conductor wire expansively engages the outer wall of the semispherical member 1 and has one of its ends extending upwardly 10 and through the inner wall 2 as at 12 above the raceway portion 13 for the conductor mercury, and thence downwardly to the binding post 14. Mercury is placed in the mercury raceway 13 and as the semispherical member 1 is oscillated by means of the eccentric 15, which rotates in the eccentric yoke 16, which extends downwardly from the lower end of the tube, said mercury will move around the raceway 13 in contact with 15 the conductor wire 11, and as the mercury, during its rotation, engages the conductor wires 6, which extend into the chambered members 3, circuits are intermittently made and broken as desired. Although a limited 20 number of conductor wires 6 and chambered members 3 are shown, it is to be understood that any number desired may be used, however a limited number are shown for purposes of illustration. Eccentric 15 is carried by a sleeve 17 rotatably mounted on the post 9, and which sleeve is provided with a pulley 18, around which a belt may extend, which may lead to any source of power for operating the device, for instance a motor. 25 It will be seen that the tube is balanced in a manner whereby a minimum amount of power or force will be required to actuate the same, and in which the required movement consists merely in a circular tilting movement of the tube or semispherical member 1 about a fixed axis. It will also be seen that a switch is provided in which the surface tension of the conductive fluid is utilized to effect a rapid separation of the 30 poles at the instant of breaking the controlled circuit.

The inner wall 2 on its inner side is provided with a reserve reservoir 19, which is preferably hermetically sealed at 20, and in which reservoir a reserve supply of mercury is placed, which may be added from time to time to the mercury body 21 by tilting the device so that the mercury will pass through the aperture 22 in communication with the chamber 10, therefore it will be seen that the mercury body may be increased in volume or if desired, decreased, for operating as many contacts as necessary or desired, or bring about proper contact of the 35 40 45 50 55 60 65 70 75 80 85 90 95 100 105 110 115

terminal wires and the electric current supply wire 11.

Extending outwardly and downwardly from the supporting post 9 is an angularly shaped guide arm 23, which guide arm extends through an elongated slot 24, in one of the arms 25 of the yoke 16, therefore it will be seen that the semispherical member 1 will be held against rotating with the eccentric 15 during the rotation of said eccentric as the post is stationary, but at the same time the slot 24 is relatively wide, consequently the angularly shaped arm 23 will not interfere with the tilting oscillating movement of the semispherical member during the rotation of the eccentric.

From the above it will be seen that an electric switch is provided which is a departure from conventional forms of conductive fluid switches, and a switch more positive and accurately controlled by reason of the part circular tilting movement of the specially designed double wall tube, which positively controls the conductive fluid in closing and opening terminal poles. It will also be seen that additional mercury may be easily and quickly added to the mercury in the raceway or removed therefrom. The unoccupied portion of the chamber 10 is preferably filled with an inert gas, a gas which has no chemical affinity for the mercury or for the material in the tube, and which gas is approximately at atmospheric pressure.

The invention having been set forth what is claimed as new and useful is:

1. An electric switch comprising an inverted semispherical double wall member having a chamber therein and a fluid raceway adjacent its lower end, a supporting member, said supporting member having an axially disposed bearing within the inverted member, a conductor member within the inverted member adjacent the raceway, a downwardly extending yoke carried by the inverted member, a rotatable eccentric cooperating with said yoke for oscillating the inverted member, a guide arm for guiding said inverted member in its oscillatory movement and a plurality of conductor members extending into the depression in the bottom of the raceway.
2. The combination with an oscillatory fluid switch having a fluid raceway, of an auxiliary reserve reservoir carried thereby and means whereby fluid from the raceway may be removed or fluid placed therein.

In testimony whereof I affix my signature.

HENRY A. HOESCHEN.
